UNITED STATES PATENT OFFICE.

JOHN B. HAIN, OF EDGERTON, WISCONSIN.

HOLDBACK FOR VEHICLES.

SPECIFICATION forming part of Letters Patent No. 406,043, dated July 2, 1889.

Application filed October 2, 1888. Serial No. 286,973. (No model.)

To all whom it may concern:

Be it known that I, JOHN B. HAIN, of Edgerton, in the county of Rock and State of Wisconsin, have invented new and useful Improvements in Holdback Attachments for Vehicles; and I do hereby declare the following to be a full, clear, and exact description of said invention, reference being had to the accompanying drawings, and to the letters or figures of reference marked thereon, which form a part of this specification.

My invention relates to improvements in holdback straps and irons for single carriages, and pertains to the construction of the holdback-iron and the combination and arrangement of the holdback-iron with the thill, the holdback and thill-supporting straps.

The construction of my invention is explained by reference to the accompanying drawings, in which—

Figure 1 represents a side view of my invention as shown upon one side of the vehicle, a duplicate of the same being shown upon the opposite side. Fig. 2 represents a longitudinal section of the holdback-iron removed from the thill. Fig. 3 represents a top view of the iron shown in Fig. 2. Fig. 4 is a detail showing the manner of connecting the holdback-strap with the thill-supporting strap.

The holdback-iron consists of the plate A, the downward and forward projecting strap-hook B, which is riveted or otherwise rigidly secured to the plate A, the swinging arm or keeper C, which is pivoted to the plate A by trunnions D D, operating in the recesses E E, formed therefor in the upper side of the plate A, and spring F, which is secured to the upper surface of the plate A within the chamber G by a retaining-rivet H. The chamber G is formed for the reception of both the spring F and the pivoted end of the keeper C, whereby the required space is provided for the movements of the spring and keeper. The spring F may be formed of a single plate, but is preferably formed of two thin plates arranged parallel to and in close contact with each other. The object of using two plates instead of one is to attain greater elasticity and strength, with less liability of the spring being broken than would be the

case with a single spring of equal heft. The pivoted end of the arm or keeper C is provided with a spring-retaining notch or recess a for the reception of the bearing end of the spring, whereby said keeper C is retained in contact with the lower end of the strap-hook B. A small recess or aperture b is formed in the lower end of the keeper C for the reception of the stud d, formed on the lower end of the strap-hook B, whereby, when said keeper C is in a closed position, said stud d resists all such side or lateral strain as may be brought to bear upon the swinging end of said keeper, whereby the strain, which would otherwise be brought to bear upon the pivots D D, is prevented.

I is a shoulder formed on the front side of the retaining-keeper C, and serves as a stop to said keeper in its forward movement as the holdback-strap is being withdrawn from the strap-hook B.

J is the holdback-strap, which is connected at its rear end with the rear part of the harness in the ordinary manner, and its front end engages upon the strap-hook B.

K is the ordinary thill-strap of the harness by which the front end of the thill is supported.

To provide for disengaging the holdback-strap J from the hook B automatically when the horse is unhitched and led forward, I have connected the front end of the holdback-strap J with the thill-strap K by a connecting-strap L, whereby it is obvious that, the traces of the harness being disengaged and the horse being led forward, the front end of the holdback-strap J will be drawn downward and forward by said strap L and disengaged from the hook B. The rear end of the strap L is provided with a buckle M, which engages or buckles into the inner fold of the holdback-strap J at a slight distance in rear of the strap-hook B, as shown in Fig. 4, whereby said strap L is prevented from becoming entangled with or getting in front of the strap-hook B.

Having thus described my invention, what I claim as new, and desire to secure by Letters Patent, is—

The combination of the thill B' with the holdback attachment, consisting of the plate

A, keeper-retaining springs F, and keeper C, with the holdback-strap J, thill-strap K, and connecting-strap L, said holdback-strap J being connected at its front end with the strap-
5 hook B and at its rear end with the rear part of the harness, said strap L being connected at its rear end with said strap J and at its front end with said holdback-strap K, all substantially as and for the purpose specified.

In testimony whereof I affix my signature in presence of two witnesses.

JOHN B. HAIN.
